UNITED STATES PATENT OFFICE.

FREDERICK C. BLANCHARD AND PHILIP G. DARLING, OF BRIDGEPORT, CONNECTICUT,
ASSIGNORS TO THE CONSOLIDATED SAFETY VALVE COMPANY, OF BRIDGEPORT, CONNECTICUT, A CORPORATION OF CONNECTICUT.

COVER-RING FOR VALVES.

No. 917,920.

Specification of Letters Patent. Patented April 13, 1909.

Application filed January 2, 1909. Serial No. 470,509.

To all whom it may concern:

Be it known that we, FREDERICK C. BLANCHARD and PHILIP G. DARLING, citizens of the United States, and residents of Bridgeport, in the county of Fairfield and State of Connecticut, have invented new and useful Improvements in Cover-Rings for Valves, of which the following is a specification.

This invention relates to safety valves and more particularly to cover rings for use in that type of safety valves wherein the valve is provided with an upwardly extending cylindrical flange in sliding engagement with the cover containing the valve spring.

In valves of the class described, the cover is made almost invariably of cast iron, and in actual use usually rusts within a very short time after it has been placed in service. Consequently, it has proved to be an annoying, expensive and even dangerous practice to so construct the valve that its upwardly extending cylindrical flange shall slide directly on the surface of the cover; for the rust upon the latter tends to hold the cylindrical flange of the valve and thus prevent it from opening when the predetermined popping pressure has been reached on the valve. To overcome this difficulty a ring of bronze or similar material has sometimes been placed around the bottom end of the cover in order to insure a smooth surface upon which the cylindrical flange of the valve may slide. The use of said bronze cover ring has not however solved the difficulties encountered, but on the contrary has proved most unsatisfactory in practice because of the difficulties and annoyances experienced in securing it upon the cover in such manner that it will not work loose and fall down upon the head of the valve thus rendering the valve useless. The ordinary press fit sometimes employed for securing the cover ring, has proved a failure due to the fact that the bronze expands more than the cast iron of the cover and therefore the ring soon works loose and drops down; and when screws are employed for this purpose, the continual expansion and contraction of the bronze and cast iron causes the screws to work loose, and even break off.

The object of this invention is to obviate these difficulties and to that end to provide a cover ring which will insure a smooth surface upon which the cylindrical flange of the

valve may slide and which cannot possibly 55 work off from the cover.

Referring to the drawings,—Figure 1 is a sectional view of a valve showing our improved cover ring; and Fig. 2 is a sectional view of the cover ring before it has been secured to the cover.

In the drawings, A is a valve casing provided with a valve seat in which the valve B is seated.

C is the cover mounted upon the casing A 65 and provided with an annular skirt C' projecting toward the valve B. Within the cover C is the spring D which holds the valve on its seat in the usual manner.

E is the cylindrical flange of the valve B 70 projecting upward into the steam passage F and, in the embodiment of our invention shown in the drawings, outside of and in sliding engagement with the cover ring G secured to the bottom end of the skirt C' of the 75 cover C.

The cover ring is turned straight from bronze or similar material and is provided with a shoulder g and an annular rabbet g'.

In assembling the parts of the valve, the 80 cover ring G is pressed onto the skirt C' until the shoulder g engages the shoulder c in the skirt C'. The annular rabbet g' of the ring is then spun down with a roller tool, or other suitable means, against the inclined surface 85 of the inset or groove c' in the skirt C', thus clinching the ring securely upon the cover.

By this construction a cover ring is provided which is inexpensive, easily and quickly secured to the cover, and which 90 when secured cannot be injuriously affected by the expansion and contraction of the opposed bronze and cast iron of which the ring and cover are respectively made.

What we claim is:

1. In a valve, a valve casing provided with a valve seat, a valve coöperating with said valve seat, a cover, a cover ring clinched upon said cover and said valve having a flange in sliding engagement with said cover 100 ring.

2. In a valve, a valve casing provided with a valve seat, a valve coöperating with said valve seat, a cover provided with an annular inset, a cover ring having an annular rabbet, 105 said annular rabbet clinched within said annular inset and said valve having a flange in sliding engagement with said cover ring.

3. In a valve, a valve casing provided with a valve seat, a valve coöperating with said valve seat, a cover provided with a shoulder and an annular inset having an inclined surface, a cover ring provided with a shoulder and an annular rabbet, said shoulder of said ring in engagement with said shoulder of said cover, and said annular rabbet of said ring clinched down upon said inclined surface of said inset, and said valve having a flange in sliding engagement with said cover ring.

4. In a valve, a valve casing provided with a valve seat, a valve coöperating with said valve seat, a cover, a cover ring clinched upon said cover and said valve having a flange outside of and in sliding engagement with said cover ring.

5. In a valve, a valve casing provided with a valve seat, a valve coöperating with said valve seat, a cover provided with an annular inset, a cover ring having an annular rabbet, said annular rabbet clinched within said an-

nular inset and said valve having a flange outside of and in sliding engagement with said cover ring.

6. In a valve, a valve casing provided with a valve seat, a valve coöperating with said valve seat, a cover provided with a shoulder and an annular inset having an inclined surface, a cover ring provided with a shoulder and an annular rabbet, said shoulder of said ring in engagement with said shoulder of said cover, and said annular rabbet of said ring clinched down upon said inclined surface of said inset, and said valve having a flange outside of and in sliding engagement with said cover ring.

Signed by us at Bridgeport, Connecticut, this 30th day of December, 1908.

FREDERICK C. BLANCHARD.
PHILIP G. DARLING.
